UNITED STATES PATENT OFFICE.

CHARLES E. MILLER, OF CHICAGO, ILLINOIS, ASSIGNOR TO UNIVERSAL ARCH COMPANY, OF CHICAGO, ILLINOIS, A CORPORATION OF ILLINOIS.

LOCOMOTIVE ARCH.

Application filed March 5, 1920. Serial No. 363,463.

To all whom it may concern:

Be it known that I, CHARLES E. MILLER, a citizen of the United States, and resident of Chicago, in the county of Cook and State of

5 Illinois, have invented certain new and useful Improvements in Locomotive Arches, of which the following is a specification.

10 My invention relates to improvements in combustion chambers for steam boilers and has special reference to an improved refractory arch or baffle for use in a locomotive fire box.

15 It is usual to provide inclined water tubes in a locomotive fire box which extend from the lower part of the flue sheet rearwardly and upwardly to the rear fire box sheet, for increasing the production of steam and causing a forced circulation of the water in the boiler.

20 It is common practice to arrange refractory slabs or fire bricks on these inclined tubes to provide a refractory arch or baffle between the grate and the flue sheet to cause the burning fire box gases to rise into contact with the crown sheet and the side sheets 25 of the fire box on their way to the flues which lead forward through the boiler to the smoke box at the forward end.

25 The early arches of this character were 30 made of large flat slabs laid directly on the inclined tubes and reaching substantially from side sheet to side sheet. These large slabs were not satisfactory in that they were difficult to get into the fire box and to place 35 in position and were subject to quick deterioration and destruction, soon breaking to pieces and falling down into the fire. The next step was to build the arch of small bricks or pieces adapted to be put into the fire box 40 through the ordinary fire door and adapted to span from tube to tube and having inclined ends for contact with the tubes which lent a degree of adjustment between the spacing of adjacent tubes and the lengths of 45 the bricks.

It was found that a solid or tight built arch with the bricks laid close together did not give the best results and that it was desirable to space the bricks apart longitudinally of the tubes to permit some of the gases to pass directly through the arch. The advantage of this is that these streams of hot gases passing through the arch cause a thorough mixing of the gases flowing around 50 and over the arch and serve to maintain a

higher temperature in the fire box between the arch and the flue sheet and prevent the cooling of the main body of gases to a point below ignition.

It has been proposed to space the bricks 60 on the tubes and retain them in spaced relation by means of small or short U-shaped spacing blocks adapted to hang on the tube between the arch bricks. These small spacer bricks have not proven satisfactory. They 65 are too fragile and easily displaced frequently turning around on the tubes and falling off and as it is necessary to clear the holes through the arch from time to time of slag and other obstructions, these small fragile 70 spacing blocks are subject to be cracked, broken and displaced and the arch thus destroyed. When these spacer blocks are displaced the arch bricks become displaced by 75 sliding down the inclined tubes and frequently they fall off of the tubes thus displacing the arch.

By means of my invention I eliminate all 80 of the detrimental features above mentioned. I provide a locomotive fire box arch which is substantially permanent, once it is installed; which has an even distribution of perforations over its entire area, the several bricks 85 having integral spacing projections on their tube supported ends, which projections not only hold the bricks in position but the lateral edges of the bricks are cut away between the projections and when the bricks are placed in position these cut away portions form the perforations or slots extending through the arch from the under side to the top or back of the arch.

I have embodied several other features 90 in the brick and arch of my invention, which tend not only to reduce manufacturing costs, 95 but also to add endurance or life to the arch as well as to add greatly to the efficiency of the arch in its function of assisting in causing and maintaining perfect combustion and protecting the inclined tubes from the scouring or cutting effect of the blasts of high temperature burning gases and the solid fuel particles carried thereby and impinging directly thereon.

I make the individual bricks of which I 100 build my improved arch of a peculiar arched form which simulates to some extent the arch of the bridge, the ends being thin and the middle portion being considerably thickened and arched up. This form not only 105

makes a brick and an arch which is exceedingly durable but in a sense provides troughs for the rising gases between the inclined tubes which troughs are maintained at a 5 maximum temperature and serve to ignite the gases as they rise into contact therewith. This formation also serves, to some extent, to protect the tubes from the hottest and most destructive gases.

10 The peculiar shape which I use provides a sharply defined longitudinal center plane of the brick of maximum thickness, thus providing the greatest thickness at the point of greatest abrasion and deterioration as 15 well as at the point of greatest strain, and consequently the brick is long lived.

The ends of my improved brick are cut out at their lower edges to provide grooves curved to substantially fit the tubes upon 20 which the bricks are supported and the upper edges at the ends of the brick extend over the tops of the tubes, substantially to the center plane thereof. This construction permits of a degree of variation in the spacing of the tubes without necessitating different lengths of bricks and also covers and protects the upper sides or tops of the tubes against the abrasive and cutting action of 25 the gases flowing over the top and down the back of the arch.

30 My invention will be more readily understood by reference to the accompanying drawings illustrating my invention and in which:

35 Fig. 1 is a diagrammatic horizontal section of a locomotive fire box equipped with a refractory arch constructed of my novel arch brick and embodying my invention;

40 Fig. 2 is a top plan view of one of the arch bricks; and,

Fig. 3 is an end elevation of one of the arch bricks.

In said drawing, 1 represents the fire box 45 of a locomotive boiler, having a flue sheet 2 at its forward end a rear sheet 3 at its opposite end and side sheets 4.

The fire box is provided with a number of substantially parallel water circulation tubes 5 which extend from the lower part 50 of the flue sheet to the upper part of the sheet and assist in the rapid production of steam and the rapid circulation of the water in the boiler.

Upon the forward ends of the tubes 5 I 55 construct a refractory arch 6 made up of a plurality of transverse and longitudinal rows of refractory arch bricks of two forms, 7 and 8. The bricks 7 span from tube to tube and the bricks 8 fill in between the side tubes and the side sheets of the fire box.

The center bricks 7 are all substantially identical in that they are all of the same pattern and where the tubes 5 are parallel, as shown, they are of uniform size.

60 65 As the fire box widens toward the flue

sheet the side bricks may vary somewhat in length in the several transverse rows, but even so they have several of the characteristics of the bricks 7.

The arch bricks 7 rest at their ends on 70 the tubes 5 and are provided at the lower edges of their ends with quarter circle grooves 9 substantially fitting the outer surface of the tubes and arranged to extend substantially to the top of the tubes and 75 down to about the middle of the tubes, so that the brick is not only supported by the tubes upon which it rests, but is also held against movement transversely of the fire box.

The brick thus formed is practically provided with end shoulders 10 which engage the sides of the tube 5 and hold the brick against movement transversely of the fire box and with supporting flanges 11 at their 80 ends which rest upon the tubes and cover them. The spacing of the two grooves 9 is such in reference to the spacing of the tubes that slight lateral play or clearance is provided between the tubes and the shoulders 19 85 to allow for expansion of the bricks and to allow for some variation of the spacing of the tubes.

The brick is arched or curved upwardly 90 from the supporting ends forming a true arched brick and in which form the brick can be made considerably lighter than the old form of flat wedge brick and yet maintain or even increase its supporting strength.

I preferably form the under surface 12 100 of the brick on a curve struck from a single center 13 and of a radius of a length to raise the center point 14 of the brick substantially to the level of the top surface of the tubes upon which the brick rests. Instead of forming the upper surface 15 of the brick on a single curve or one parallel with the under surface, I preferably strike it from two centers 16, each on the opposite side of the vertical center line from the part of the brick formed thereby and of less length than the radius of the under surface. By this means I form an arched brick which is considerably thicker at its center than at its ends and which increases to a sharply defined maximum thickness at the transverse center plane of the brick.

105 It is well known that the scouring action of the rising fire box gases and the impingement on the under side of the arch of the solid particles of fuel carried upward by the excessively strong forced draught used in locomotive practice tend to wear away the under side of the arch bricks.

An arched brick formed as above described, has a longer life than one of uniform form thickness from end to end and made flat for being arched and consequently self-bracing, it will usually remain uncracked and in active service even after the middle 110

portion has been reduced to a thickness even less than the thickness at the ends of the brick.

It is to be noted that as the flanges at 5 the ends extend substantially to the centers of the tubes the tops of the tubes are not exposed between the ends of the bricks and the back of the arch is not provided with fissures or cracks for the accumulation of 10 slag, etc., as is the case with arches built with the old form of wedging bricks. Also 15 that bricks of the type shown do not produce a spreading or wedging action to spread the tubes apart, the tubes merely carrying the weight of the bricks and not 20 holding them up by a wedging action.

As explained hereinbefore, it is advisable 25 to provide the arch with openings extending through the arch from the lower side 30 to the upper side or back of the arch and for this purpose I provide the bricks with spacing projections 18 at their ends extending longitudinally of the tubes. Between 35 the projections 18 the sides of the brick are cut away to provide shallow recesses 19 extending from the under side to the back of the brick. When the bricks are assembled on the tubes 5 the recesses 19 in adjacent bricks between or resting on the same 40 tubes form openings 20 in the arch through which the gases of combustion can flow directly from the fuel bed to the back of the arch.

These streams of burning gases which 45 thus flow through the arch at many points are at substantially maximum temperature, they are usually overcharged with oxygen and by means of the strong forced draught used in locomotive practice these streams are 50 projected with considerable force into the body of combustion gases flowing down the back of the arch toward the flue sheet. This plurality of thin narrow streams of combustion gases rising through the openings 55 20 cause the thorough intermingling and mixing of the body of gases, probably adding oxygen, and assisting in maintaining the temperature of the main body of gases up to the combustion temperature and consequently resulting in the thorough and complete combustion of the fuel.

The side bricks 8 are supported at their 60 inner ends on the outer tubes and are usually leaned against the side sheets in an upwardly inclined position as indicated, but however they are supported they are likewise provided with the integral spacing projections 18 and formed with the recesses or 65 spaces 19 in their lateral edges, thus provid-

ing the arch with the openings 20 between 60 the outer tubes and the side sheets as well as in the parts of the arch between the tubes.

It is desirable that considerably enlarged 65 openings 21 be provided between the lower or forward end of the arch and the flue sheet to permit relatively large streams of the burning gases to flow around the lower end of the arch into the lowermost of the 70 boiler tubes 22. For supporting the arch thus spaced from the flue sheet I provide 75 filler or spacer blocks 23 adapted to be supported on the tubes 5 and held tightly between the arch and the flue sheet 2. As the whole downward thrust of the arch is sustained by these blocks they are securely held in position and are not subject to destruction and displacement as the relatively 80 small U-shaped spacer blocks ordinarily used to hold the several transverse rows of the 85 bricks apart and provide openings in the arch.

It is obvious that the novel features involved in this invention are capable of taking many different forms and I do not limit or confine my invention to the specific 85 forms or constructions herein shown and described.

I claim:

1. A refractory arch brick for support 90 upon water tubes in a fire box, the ends of the brick having quarter circle grooves for receiving the supporting tubes, and the brick arched up between its ends, the middle part 95 of the brick being thicker than its ends, substantially as described.

2. A refractory arch brick adapted to be supported upon water tubes in a fire box, the under surface of the brick being formed upon a curve struck from a center in the vertical center plane of the brick, the upper surface of the brick formed upon two curves each struck from a center located on the opposite side of the vertical plane of the brick and of shorter radius than that of the lower side whereby the brick is thicker at its middle portion and tapers towards both ends, substantially as described.

3. A refractory arch brick of the kind described having tube receiving grooves at its ends and being arched up between its ends, the brick being thickest at its middle portion and curved downwardly and tapered toward each end, substantially as described.

Signed at Chicago, Illinois, this 2nd day of March, 1920.

CHARLES E. MILLER.
